UNITED STATES PATENT OFFICE.

BENCE O. BROWN, OF COLORADO, TEXAS.

NECKTIE-PRESSER.

1,164,462.

Specification of Letters Patent. Patented Dec. 14, 1915.

Application filed February 15, 1915. Serial No. 8,276.

To all whom it may concern:

Be it known that I, BENCE O. BROWN, a citizen of the United States, residing at Colorado, in the county of Mitchell and State 5 of Texas, have invented certain new and useful Improvements in Necktie-Pressers; and I do hereby declare the following to be a full, clear, and exact description of the invention, such as will enable others skilled 10 in the art to which it appertains to make and use the same.

This invention relates to necktie pressers, and the principal object of the invention is to provide a device of simple construction 15 which will hold a number of scarfs or neckties flat and will press them so that they will always be in proper condition for wear.

When neck scarfs or neckties are worn a short time they become very much wrinkled, 20 and if properly pressed out they make a neat appearance. It is troublesome and sometimes expensive to have a number of neckties or scarfs ironed out.

The principal object of this invention is 25 to hold the scarfs after they have been taken off the wearer in a press which will keep them smooth and in proper condition for wear.

The foregoing and other objects may be 30 attained by means of the construction illustrated in the accompanying drawing, in which the figure of the drawing is a perspective view showing a necktie presser made in accordance with this invention.

35 Referring to the drawing, the numeral 1 designates a cross head or hanger, provided with a suspending hook 2 at the center thereof. Projecting from the opposite sides of the cross heads 1 near the bottom thereof are 40 pintles 3, and pivoted upon said pintles are metal hanger plates 4 and 5, said plates having curved upper ends 6. Secured to the lower ends of the hangers 4 is a board 7 having a mirror 8 on the outer face thereof.

45 Connected to the hangers 5 is a plain board 9. A central presser board 10 is connected by suitable hangers 11 to the pintles 3, said hangers carrying springs 12. The springs 50 12 have a tendency to force the members 7 and 9 outward when released at the lower end. A rod of wood or metal 13, extends

across and is secured to the hangers 4, and the scarfs or neckties 14 are doubled in the center or hung on the rod 13 and extend upon opposite sides of the presser board 10. 55 Any suitable number of scarfs or ties may be suspended from the rod 13 and pressed between the members 7 and 9 against the presser board 10. After the ties have been placed in position the members 7 and 9 are 60 closed up against the ties upon opposite sides of the presser board 10 and said members are locked in place by means of bolts 15 pivotally connected to staples 16 at the opposite sides of the board 9, said bolts adapted to 65 engage slots 17 formed in a cross bar 18 on the front member 7. A knob or handle 19 projects from the lower end of the member 7.

From the foregoing it will be obvious that a necktie presser made in accordance with 70 this invention is comparatively simple in construction, inexpensive to manufacture, and will operate efficiently to press a number of scarfs or ties at the same time and permit any one of them to be removed for wear. 75

By turning the thumb nut α , after the bolts 15 have been swung into the slots 17, any suitable pressure may be applied to the members 7 and 9 against the pressure board 10 and the scarfs or ties. 80

Various changes may be made in the details of construction without departing from the spirit and scope of the invention as defined in the claims.

What is claimed is:—

85 1. A necktie presser comprising a cross head, pintles extending from the sides of the cross head, hangers pivoted on the pintles, presser boards connected to the hangers, springs for throwing said presser boards outward, a central board, a rod connected to the hangers for the front board, means for adjusting and locking the two outer boards against the central board, said means comprising a slotted cross bar secured to one 90 of the boards and pivoted bolts connected to the other board and winged nuts for adjusting said presser boards against the central board. 95

100 2. A necktie presser comprising a central board, a cross head, a front member and a rear member pivotally connected to the cross

head, and comprising boards, one of said boards having a mirror thereon, a rod for suspending ties, springs for forcing said boards apart when unlocked, and means for locking said boards together against the central board.

In testimony whereof I affix my signature in presence of two witnesses.

BENCE O. BROWN.
